UNITED STATES PATENT OFFICE.

BURTON S. HUGHES, OF LOCKLAND, AND CLARENCE T. HUGHES, OF CINCINNATI, OHIO, ASSIGNORS OF ONE - THIRD TO THOMAS K. PETERS, OF ST. LOUIS, MISSOURI.

APPARATUS FOR CLEANING TUBES.

SPECIFICATION forming part of Letters Patent No. 787,333, dated April 11, 1905.

Application filed September 27, 1901. Serial No. 76,754.

To all whom it may concern:

Be it known that we, BURTON S. HUGHES, residing at Lockland, and CLARENCE T. HUGHES, residing at Cincinnati, in the county of Hamilton and State of Ohio, citizens of the United States, have invented certain new and useful Improvements in Apparatus for Cleaning Tubes, of which the following is a full, clear, and exact description, reference being had to the accompanying drawings, which form a part of our specification.

Our invention relates to apparatus to be used for removing scales from tubes of boilers and the like, more particularly from the interior of water-tube boilers; and it consists of the combination of a rotary electric motor especially adapted to the purpose with a centrifugally-operating cleaning device and of the novel construction of the cleaning device. A device of this character must be strong and of simple construction and also be capable of ready adjustment automatically to the varying conditions of use; and our invention consists in the novel construction and combination of parts, as will be hereinafter more particularly pointed out and claimed.

Heretofore the tool or device for cleaning and removing the scale from the interior of boiler-tubes has been generally and almost universally operated by a water turbine or motor. These water-motors being necessarily of small diameter, in order to enter the tube to be cleaned, are of comparatively small efficiency and do not develop anything like the power which may be advantageously employed in connection with the centrifugally-operating tools in use. Besides, a great deal of water-power is necessary to operate these water turbines or motors—in fact, a greater power than is ordinarily at hand for the purpose, and it is necessary to use a pump in order to get the required head. This makes the cleaning of boiler-tubes very expensive. In addition so much water must be used in connection with these water-turbines to clean boiler-tubes that the room or building in which the boiler is located is usually flooded, and when the boiler is located in the basement or

cellar, as is frequently the case, it is necessary to pump out the water after the boiler has been cleaned, which increases the expense in connection with the use of a water-motor.

To obviate the disadvantages and expense incumbent on the use of a water-motor, we have designed and constructed an electric motor of such form and method of operation that when connected with a centrifugally-operating tool it may be caused to enter the tube to be cleaned and to follow the tool through the tube. We find that by the use of an electric motor we can obtain a great deal more power than by the use of other means at a greatly-reduced cost. Besides this the electric current necessary to operate the motor is of potential such as is ordinarily to be obtained from any light-station. The means adopted for pushing the electric motor and tool through the boiler-tube is the ordinary flexible tube at present in use with other devices of this kind, which also serves for a conduit through which to pass the wires to the electric motor.

We also prefer to use in our apparatus a novel construction of centrifugally-operating tool, which is connected in any convenient manner to the shaft of the electric motor.

In the drawings, Figure 1 is a longitudinal section of the ends of our improved motor. Fig. 2 is a cross-section of the motor, taken on the line X X of Fig. 1. Fig. 3 is a cross-section taken on the line Y Y of Fig. 1. Fig. 4 is an elevation of our improved cleaner-head, taken at a point to illustrate the cutter disks or wheels. Fig. 5 is a section of one of the cleaner-heads, taken on the line 5 5 of Fig. 4. Fig. 6 is a partial elevation of our improved cleaner-head looking at the same from the side through which the bolt B passes, which pivots a series of the cutter-heads, the view being to more clearly illustrate the locking mechanism for the various cutter-heads. Figs. 7 and 8 are side elevations of a portion of the cutter-head to more clearly illustrate the slot and lug comprising the locking mechanism. Fig. 9 is a general side elevation showing our improved cleaner connected to the motor with the tube for advancing it

through the boiler-tube, and Fig. 10 is a detail view showing another mode of attaching.

Like letters of reference indicate like parts in the various figures.

5 We shall first take up the description of our improved cleaner-head, in which A is the frame, preferably constructed of dropped forged steel, forming the two end pieces of the cutter-head, and are connected together by 10 bar A', Fig. 5, which, as will be seen, passes through the center from end to end. Also passing from end to end are bolts B B, upon which are pivoted and free to swing or oscillate the pieces or carriers C, as can more 15 clearly be seen in Fig. 5. The cutter-heads C C C are arranged in pairs, as illustrated in Fig. 5, and in Figs. 4 and 6 we have shown three pairs of cutter-heads, though of course there is no reason why there might not be 20 only two pair or any number of sets, as desired. It will be noted that the cutter-heads on one side will swing in one direction and those on the other side in the other direction by reason of the two bolts or pivots B B. We prefer 25 in constructing our improved cutter-head to have the outward or free end of the head to be a little within the circle whose diameter would be taken at a point in Fig. 5 passing through the central bolt A' and the two pivot- 30 bolts B B in order that when the head swings outward the outer end will not come into contact with the tubes of the boiler in advance of the cutter-disks D, as would be the case if the free end of the cutter-head would extend out as 35 far when in its normal position as the pivoted point of the outside head. These carriers or heads C C have recesses into which are fitted sets of steel cutter-wheels D, preferably of the saw-tooth construction illustrated, these cutter-wheels of course being mounted upon the 40 small shafts or pins a, (Fig. 5, and illustrated in dotted lines in Fig. 4,) which have their bearing in the pieces C, being preferably riveted therein, but permitting the cutter-wheels 45 to revolve. The one end of the cutter-head frame is provided with a screw-threaded recess, as illustrated at b, Fig. 4, this end being intended to screw onto the shaft of the motor, whereby the same is to be propelled. As will 50 be seen in Fig. 4, a series or group of cutter-wheels D are employed to more efficiently, perform the object for which our invention is intended.

As the cutter-head is rapidly revolved it 55 is of course apparent that the pieces or members of the heads C C C containing the cutter-wheels D will swing outwardly, bringing the cutter-wheels D into contact with the walls of the tube or casing through which the 60 same is being operated, and the cutter-wheels with their pointed teeth or serrated edges cut any foreign substance which may have formed on the walls of the tube and also polish the tubes themselves.

65 As it is necessary to revolve the cutter-head

at a high rate of speed in order that it may perform efficient work, it necessarily follows, of course, that considerable friction is encountered, and the strain on the cutter disks or wheels D is often so great that breakage of 70 the cutter-wheels is liable to occur or by reason of the friction the teeth considerably reduced. This occurring, the portions or members of the heads C C would then themselves be thrown into contact with the walls of the 75 tube and the same be worn down by reason of the frictional contact. To avoid this contingency, we provide locking mechanism which comprises a lug c, formed on the end piece A, which fits into a recess or slot in the 80 adjacent piece C, which piece C in turn has a lug c', fitted into a slot in the piece C adjacent thereto. (See Figs. 6, 7, 8.) These lugs and recesses are so constructed that they permit the pieces or members of the heads C to swing 85 out sufficiently to bring the cutter-wheels into contact with the walls of the tube; but should the cutter-wheels be reduced or broken the lugs or shoulders c c' c'' are brought into contact with the adjacent pieces C and prevent 90 their further outward movement or swing, so as not to permit the pieces C to be brought into contact with the walls of the tube.

We shall now briefly describe the construction of the motor which we employ with our 95 improved cutter-head or cleaner. In using cutter-heads for the removal of scales from the interior of water-tubes it is necessary also to pass water through the tube in order to reduce the friction and cool off the cutter-wheels and permit them to do efficient work. It will therefore be apparent that a motor 100 must be employed which is water-tight, as the motor is also inserted in the tube to be cleaned and fed therethrough.

The motor comprises the main castings E, which form the frame and also the poles, as shown in Fig. 3. The castings or frame E are clamped together by a threaded nut E', Fig. 1, at each end of the motor, and these 105 nuts are held in place by the lock-nuts F at the two ends. The joints between the castings E E must of course be made absolutely water-tight, and this can be accomplished by grinding the faces very true, making the joint 110 absolutely tight. The connections to the motor are made through the wires or leads d, which pass through the insulated ducts or tubes e in the end of the casting, and these 115 leads or wires d terminate in the contact-points f, the latter being in contact with the contact-points f' at the end of the feed-wire h.

g represents soft-rubber disks, which act as insulators and also to prevent any water from working its way into the motor through the 120 ducts e. The portion of the motor G for supporting the feed-wires and ducts, it will be seen, is securely clamped up against the soft-rubber disks g by the lock-nut F, thus making 125 a water-tight joint. In the drawings we 130

have shown the shaft H provided with roller-bearings at its ends, though of course other bearings, such as ball-bearings, might be provided. The remainder of the motor comprises the usual armature I, commutator J, and brush and brush-holder K, and the field-coils L.

In practice the cutter-head comprising the pieces or heads C C C with the cutter-wheels 10 D is screwed onto the end of the shaft H and then inserted into the tubes of the boiler and the motor set in motion, whereby the cutter-head is rapidly revolved, bringing the cutters into contact with any scales that may 15 have formed in the tubes.

We have thus illustrated and described what we believe to be the best form of construction, though it is apparent that the construction of motor as well as the cutter-head 20 may be slightly modified.

We do not wish to be understood as limiting ourselves to the exact construction herein set forth and described, but

What we do wish to claim, and secure by 25 Letters Patent, is—

1. In apparatus for cleaning boiler-tubes, a centrifugally-operating tool, consisting of end plates, a spacing - block between said end plates, diametrically opposite rods connecting

said end plates, a series of pairs of carriers 30 pivotally mounted on said rods, the carriers of each pair being oppositely mounted, sockets in the outer face of said carriers, rotary cutters pivotally mounted in said sockets, one of the end plates and the carriers being provided at their adjacent faces with complementary lugs and sockets so as to limit the outward swing of the carriers, substantially 35 as and for the purpose described.

2. In apparatus for cleaning boiler-tubes, a 40 centrifugally-operating tool, consisting of end plates, a spacing - block between said end plates, diametrically opposite rods connecting said end plates, a series of pairs of carriers 45 pivotally mounted on said rods, the carriers of each pair being oppositely mounted, sockets in the outer face of said carriers, cutters secured in said sockets, one of the end plates and the carriers being provided at their adjacent faces with complementary lugs and sockets 50 so as to limit the outward swing of the carriers, substantially as and for the purpose described.

BURTON S. HUGHES.
CLARENCE T. HUGHES.
